CLAIM

The ornamental design for a yoga block, as shown and described.

DESCRIPTION

FIG. 1 is a front perspective view of the design of the present invention for a yoga block;

FIG. 2 is a front view of the yoga block illustrated in FIG. 1;

FIG. 3 is a top plan view of the yoga block illustrated in FIG. 1;

FIG. 4 is a back view of the yoga block illustrated in FIG. 1;

FIG. 5 is a right-side view of the yoga block illustrated in FIG. 1;

FIG. 6 is a front view of the yoga block thereof in a position of use; and,

FIG. 7 is a front perspective view of the yoga block illustrated in FIG. 6.

The left-side view of the yoga block illustrated in FIG. 1 is flat and unornamented and it does not form a part of the claim; and

The bottom plan view of the yoga block illustrated in FIG. 1 is flat and unornamented and it does not form a part of the claim.

The broken lines shown in FIGS. 1-7 illustrate the bounds of the claim and form no part of the claimed design. The broken lines showing the second yoga block in FIGS. 6-7 illustrate environment and form no part of the claimed design.

1 Claim, 5 Drawing Sheets
